UNITED STATES PATENT OFFICE.

WILLIAM P. BOYLE, OF SPRINGFIELD, MASSACHUSETTS, ASSIGNOR TO GILBERT & BARKER MANUFACTURING COMPANY, OF WEST SPRINGFIELD, MASSACHUSETTS, A CORPORATION OF MASSACHUSETTS.

BURNER.

1,256,480.

Specification of Letters Patent. Patented Feb. 12, 1918.

Application filed July 17, 1916. Serial No. 109,797.

To all whom it may concern:

Be it known that I, WILLIAM P. BOYLE, a citizen of the United States of America, residing at Springfield, in the county of Hampden and State of Massachusetts, have invented certain new and useful Improvements in Burners, of which the following as a specification.

This invention relates to fuel burners and 10 more particularly to burners of improved construction which are arranged for flexibility of operation in the use of various fuels and of fuels of varying characteristics.

An object of the invention is to provide a 15 fuel burner of improved construction which is arranged for use with either liquid or gaseous fuel or both and which is particularly characterized by an arrangement of parts, whereby liquid fuel, such as oil, for 20 example, may be introduced in a thin or attenuated gaseous mixture for enrichment purposes.

Other objects and advantages will appear in the description to follow and in the annexed claim.

For the purpose of illustrating one manner in which the invention may be practised, the preferred embodiment thereof is shown in the accompanying drawings, in which—

30 Figure 1 is an exterior elevational view of the burner;

Fig. 2 is a sectional plan view thereof taken on the line 2—2 of Fig. 1 and looking in the direction of the arrows;

35 Figs. 3 and 4 are cross sectional views taken on the lines 3—3 and 4—4, respectively, of Fig. 2 and looking in the direction of the arrows; and

Fig. 5 is a fragmentary plan view, partly 40 in section, illustrative of a modification of the burner.

Referring to these drawings in detail, the outer casing of the burner preferably 45 comprises a specially formed elbow 7, a T 8 having a male threaded portion 9 to engage in a tapped inlet in the elbow 7, and a cap 10 having a tapped opening adapted to be engaged by a second male threaded portion 11 on T 8, as clearly shown in Fig. 2. The 50 elbow 7 is divided by a partition 12 into two compartments 13 and 14 which are adapted to be supplied with fuel (such as oil, for example) and air through tapped openings 15 and 16, respectively. The portion 9 of T

8 is interiorly threaded to receive a pipe 17 55 which extends forwardly within and in concentrical relation with the T 8. The annular space 18 formed between T 8 and pipe 17 is adapted to be supplied with fuel (preferably gas) through a tapped inlet opening 60 19 in T 8. Cap 10 has formed in its face a converging opening into which a frusto conical cap 20, threaded on the forward end 65 of pipe 17, extends in spaced concentrical relation leaving an annular outlet opening 21 for the gaseous fuel.

Threaded into the partition 12 and communicating with compartment 13, as shown in Fig. 2, is a small pipe 22 which extends forwardly within pipe 17 and in concentrical relation therewith, as shown in Fig. 2. A spider fitting 23 is threaded upon the forward end of pipe 22 and has a plurality of radially arranged arms which bear against the interior surface of pipe 17 to support 75 pipe 22 therefrom; as best shown in Fig. 3.

The fuel passing through pipe 22 is discharged through a small outlet opening 24 formed in member 23. The latter has a frusto conical portion 25 arranged in 80 spaced concentrical relation with respect to cap 20 and the convergant annular passage 26 formed therebetween serves as an outlet for the air fed through pipe 17. Mounted in axial alinement with pipe 22 and coöperating with the inlet opening in partition 12 is a valve 27 which has a threaded engagement with a part of elbow 7 and extends without the latter through a suitable stuffing box for convenient actuation. 90

An advantageous feature of the burner construction described is its ready adaptability for use with either oil or gaseous fuels or both as desired. Moreover, in localities where simply gaseous fuels alone 95 are used, the burner may be easily transformed from a combination gas and oil burner to simply a gas burner, by removing the fitting 7 and substituting therefor a plain elbow 28, as shown in Fig. 5, or any 100 other suitable fitting which will serve to introduce air into the pipe 17. The pipe 22 may be also omitted, as shown in Fig. 5, but need not necessarily be removed unless desired. 105

In the normal operation of the burner, gas is supplied through suitable valve controlled pipe connections to the inlet 19, oil

through inlet 15, and air through valve controlled inlet 16, preferably under pressure. The inflow of oil may be regulated as desired by the valve 27. As the oil leaves the burner through outlet 24, it is atomized by the stream of air leaving through the annular space 26, and it is particularly to be noted that the air is directed inwardly into the stream of oil to obtain a thorough mixture by reason of the convergent passage 26. Similarly, the gaseous fuel is directed into the stream of air and oil by the convergent outlet 21 so that the two fuels are thoroughly mixed with air. By closing off the supply of gas to outlet 19, the burner may be used for oil alone and, conversely, by closing valve 27, the burner may be used for gas alone.

The burner described finds another advantageous use in the enrichment of thin gaseous mixtures. Frequently, the quality of gas supplied in certain localities and in certain plants does not possess the desired fuel value and is commonly known as "thin" gas. Or in a given place the gas may vary in quality from time to time; at one time it may be rich and at another time poor in fuel value. Such poor or thin gas may, however, be successfully used with this type of burner by using a small quantity of oil, which, when injected into the gas will bring the final mixture up to the required fuel value. The advantage of the burner is that by its use a desired flame of given heat value may be obtained at a given time and independent to a large degree of the main gas supply. The heat value of the flame may also be changed from time to time as desired. The mixing of the fuel for the flame

takes place between the nozzle and the flame. 40 The manipulation of the valve controlled passages will give a wider range than heretofore in which to adjust the flame for a given use without interfering with the main supply of gas. 45

It is recognized that changes may be made in the structure herein described for illustrative purposes without departing from the scope of the invention which is defined by the appended claim rather than by the foregoing description of one preferred form. 50

What I claim is—

A fuel burner, comprising, a casing having axially aligned openings, and an inlet 55 rectangularly arranged with respect to said openings, a tube fixed in and closing one of said openings and extending into the other thereot in spaced concentrical relation, whereby an annular passage communicating with said inlet is formed, a member fixed to the casing having a passage communicating with said tube, a pipe within the latter and fixed to said member, a valve controlled passage in the latter communicating with said pipe, a cap on the casing, a cap on the tube, 60 and a cap on the pipe, said caps arranged one within another in spaced concentrical relation and having conical surfaces whereby annular converging outlets are formed, said annular passage, tube, and pipe adapted to be supplied with air, a gaseous and a liquid fuel, respectively, all constructed and arranged for a thorough atomization of the liquid fuel and an intimate mixing of the gaseous and atomized liquid fuel with the 65 air. 70

WILLIAM P. BOYLE.
